Des. 233,481

Patented Oct. 29, 1974

233,481

XEROGRAPHIC VAPOR FUSING UNIT

Ruediger W. Knodt, Rochester, N.Y., assignor to
Xerox Corporation, Stamford, Conn.

Filed Oct. 27, 1972, Ser. No. 301,704

Term of patent 14 years

Int. Cl. D16—99

U.S. Cl. D61—1 Q

FIG. 2

FIG. 3

FIG. 4

FIG. 5

FIG. 6

FIG. 1 is a front perspective view of a xerographic vapor fusing unit showing my new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof.

I claim:

The ornamental design for a xerographic vapor fusing unit, substantially as shown and described.
